United States Patent [19]

Tarbutt et al.

US00D343390S

[11] Patent Number: Des. 343,390

[45] Date of Patent: ** Jan. 18, 1994

[54] TABLE TOP IMAGE BASED DOCUMENT PROCESSING MACHINE FOR USE WITH PERSONAL COMPUTER

[75] Inventors: Vern Tarbutt, Kitchener; Graham Marshall; Alistair Hamilton, both of Waterloo, all of Canada

[73] Assignee: NCR Corporation, Dayton, Ohio

[**] Term: 14 Years

[21] Appl. No.: 639,700

[22] Filed: Dec. 10, 1990

[52] U.S. Cl. D14/107; D18/55

[57] CLAIM

The ornamental design for a table top image based document processing machine for use with personal computer, as shown and described.

DESCRIPTION

FIG. 1 is a front perspective view of a table top image based document processing machine for use with personal computer showing our new design;

FIG. 2 is a rear perspective view thereof;

FIG. 3 is a front elevational view thereof on an enlarged scale;

FIG. 4 is a rear elevational view thereof;

FIG. 5 is a top plan view thereof;

FIG. 6 is a left side elevational view thereof; and,

FIG. 7 is a right side elevational view thereof.

FIG. 1

FIG. 2

FIG. 3

FIG. 4

FIG. 5

FIG. 6

FIG. 7
